CLOSURE DEVICE FOR CONTAINER OPENINGS

Howard W. Dodson, Philadelphia, Pa., assignor,
by mesne assignments, to United Steel Barrel
Company, Philadelphia, Pa., a corporation of
Pennsylvania

Application July 14, 1939, Serial No. 284,463

4 Claims. (CL 285—49)

The present invention relates to closure devices for openings in metal containers, such as drums, barrels, cans, tanks, or the like, and particularly for openings through which such containers, drums, barrels, cans, tanks, etc. may be filled and emptied. The present invention relates more particularly to container openings and closure devices therefor which are to be repeatedly opened and closed.

The cost of production of closure devices for container openings is frequently a vital factor bearing upon the practicability of the devices, particularly where the containers, such as the sheet-metal drums, barrels, cans, tanks, or the like are likely to be used only once for the transportation or storage of the original contents, and it is therefore important to provide not only effective closure means having sufficient structural strength, but also closure means which can be produced at low cost, and which can be made uniform by manufacturing operations not subject to failure. Since such closure devices must be made in large quantities, it is important that the construction shall be one which will be dependable in mass production.

Among the objects of the present invention is the provision of strong and durable closure means for sheet-metal containers, such as drums, barrels, cans, tanks, etc. which will be dependable and which may be produced at low cost, and in which the possibilities of failure, either in the manufacture or in the use thereof, are minimized.

With the above and other objects in view which will appear more fully from the following detailed description, accompanying drawing, and appended claims, the present invention contemplates an outwardly-projecting flange at the opening of a sheet-metal container, said flange being formed integrally with the body metal of the container and externally reinforced by a fixed cast band enveloping said flange, said reinforcing band being cast in situ in a molten state from a metal separate and distinct and different from the body metal of the container.

The present invention further consists of other novel features and principles and details of construction, all of which will appear more fully from the following detailed description, accompanying drawing and appended claims.

For the purpose of illustrating the invention, there is shown in the accompanying drawing one form thereof which is at present preferred, since the same has been found in practice to give satisfactory and reliable results, although it is to be understood that various instrumentalities of

which the invention consists can be variously arranged and organized and that the invention is not limited to the precise arrangement and organization of the instrumentalities as herein shown and described.

In the accompanying drawing, wherein like reference characters indicate like parts,

Figure 1 represents a fragmentary view, partly in section and partly in elevation, of a drum head opening and closure means therefor constituting one embodiment of the present invention.

Figure 2 represents a bottom plan view of said drum head opening and associated closure means, as would be seen for instance on line 2—2 of Figure 1 looking in the direction of the arrows.

Figure 3 represents a perspective view, on a somewhat reduced scale, of the removable screw-threaded closure plug shown in Figure 1 disassociated from the rest of the device.

According to the present invention, a hole or opening, indicated generally by the numeral 10, is formed in the sheet-metal of the head or body of the container. In the particular illustration shown, the body sheet-metal or body metal 11 is indicated as being that of the head or generally flat end of a sheet-metal container, such as a drum, barrel, can, tank, etc., although it is to be expressly understood that the present invention is equally applicable to openings formed in the more or less cylindrical sides of such containers.

The body metal at the zone of the opening is stamped or pressed outwardly to form a generally cylindrical outwardly-extending neck or flange 12, and in the illustrated embodiment of the present invention the outer marginal portion of this neck 12 is turned down to provide a peripheral gasket-seating end-flange 13.

A screw-thread of any desired pitch and outline, as for instance, the coarse rounded screw-thread 14 illustrated in the drawing, may be rolled, turned, pressed or otherwise formed along the side of the cylindrical flange 12, thereby to provide securement means for a correspondingly-threaded closure plug 15. If desired, the pitch of the thread 14 may be varied, and the thread may assume a form other than the curved form illustrated. Thus, the number of threads per inch may be increased or decreased making the thread 14 finer or coarser, and the shape thereof may assume a sharp V-shaped or other forms.

This screw-threaded flange 12 is snugly encircled by a reinforcing band or shell 16 which is cast in situ from molten metal separate and distinct and different from the body metal of the container. Thus, in accordance with the

present invention, a mold having a concavity or metal-receiving space corresponding in size to the desired cross-section of the ultimate reinforcing band is applied over the outwardly-extending screw-flange 12, with the flange acting as a core within said mold.

The particular construction of the mold and the manner of its application to the container screw-flange is not shown here, because this specification is intended to be addressed to the resultant product and the method of making the same, and not to the apparatus for practicing the method or making the product.

A relatively low melting point alloy, consisting principally of zinc, with variable amounts of aluminum, copper and magnesium, and, optionally, with some percentages of tin and antimony is then poured or forced into the mold under pressure in a molten state, and at a temperature sufficiently high to insure that the metal alloy will flow freely and will completely fill all the unoccupied space in said mold.

A suitable low melting point alloy composition for the flange-encircling band 16 may be represented by a composition of ninety to ninety-five per cent zinc and about five per cent aluminum, one to four per cent copper and about .01 to .05 per cent magnesium. These proportions may be varied according to the degree of hardness and other qualities desired.

As the molten metal hardens around the screw-flange 12, it becomes fixed relative thereto, and the casting 16 is prevented from being rotated thereon, or moved axially therealong. Thus, since the cast reinforcing band 16 closely follows the external contour of the screw-thread 14 along the side of the screw-flange 12, and since the band 16 is further axially confined between the juxtaposed end-flange 13 and the body metal 11 at the base of the screw-flange, rotary and/or axial movement of this band is prevented.

Prior to the application of the molten metal to form the flange-reinforcing band 16, the body metal, at least in the zone of the application of the molten metal, is preferably cleaned of all scale. In this manner, substantial adhesion or union or metal-to-metal bonding may be obtained between the molten metal and the body metal. This union or bonding may be further augmented or increased by initially turning or coating or plating the body metal with cadmium or zinc in the zone where the molten metal is to be applied.

If desired, any suitable additional means may be provided for further preventing or restraining the flange-reinforcing band or shell 16 from rotating or becoming loosened on the screw-flange 12. Thus, for example, anti-rotational surface irregularities may be formed in the container body metal surrounding the base of the screw-flange 12. Thus, an annular zone of the body metal disposed at the base of the screw-flange 12, may be pressed, stamped or otherwise shaped into corrugated or undulating form, to provide radially extending alternate ridges 17 and troughs 18. As the molten metal from which the reinforcing band 16 is cast is forced into the molding, it enters into and fills the troughs 18 and accordingly when the casting 16 subsequently hardens it will be further restrained from rotating on the neck 12.

The container wall around the screw-flange 12 may be structurally strengthened, if desired, by an annular ridge or raised portion 19 which may be provided by slightly off-setting the an-

nular zone at the base of the flange 12 outwardly or inwardly relative to the container wall 11.

In the illustrated embodiment of the present invention the reinforcing band 16 is cast with a generally flat annular end-surface 20 disposed in the same plane as the gasket-seating surface of the end-flange 13 and indeed in direct continuation thereof, thereby providing a relatively wide smooth and uninterrupted gasket-seating surface. A sealing gasket 21 is pressed down onto the seating surfaces 13 and 20 by the closure-plug 15, which is itself provided with an annular gasket-seating surface 22 in juxtaposition with the screw-flange end-surface 13. In use, the sealing gasket 21 is operatively compressed as the screw-plug 15 is screwed into the screw-flange 12.

By providing a gasket-seat on the body metal comprising the end-flange 13, the fluid-tight seal established when the gasket 21 is pressed down thereover will not be affected by any possible cracking or fracture of the die-cast flange-encircling band 16. Thus, for instance, the cast band 16 may become fractured or cracked anywhere along its periphery, and may even be completely broken through at one or more points, without affecting the seal established by the gasket 21, because the gasket is pressed directly against the continuous and uninterrupted body metal surface 13.

The screw-threaded closure plug 15 may be inexpensively constructed by being stamped or pressed out of blanks of suitable sheet-metal, preferably of heavier gauge than the container body metal. The particular closure-plug illustrated in the drawing is of hollow construction, and is provided at its upper end with polygonal seizure-means 23 adapted to be seized or engaged and turned by any suitable wrench or tool, thereby to tighten or loosen said plug.

After the plug 15 has been screw-threadedly engaged with the screw-flange 12 and tightened, a tamper-indicating sheet-metal sealing cap 24 may be superimposed over the plug with its peripheral edge portion 25 crimped or turned under the band shoulder 26, so as completely to prevent access to the plug 15 during transportation or storage of the container. In removing the tamper-indicating sealing cap 24, the crimped flange 25 thereof is so distorted as to make reapplication of the sealing cap impossible without detection.

In the hereinabove described construction, the plug-retaining threads are formed directly in the body metal of the container, instead of being formed in some separate annular flange or bushing secured to the mouth of the container opening, and the thread-bearing portion of the body metal is structurally reinforced by the encircling band cast in situ. Accordingly, the closure device of the present invention possesses structural strength and durability far in excess of that obtainable from the mere use of a screw-flange formed directly out of the container sheet-metal, particularly where the container sheet metal is relatively thin, as is frequently the case. Thus, the hereinabove described construction provides strong and effective container closure means which directly utilizes the body metal of the container to anchor the removable plug, and which does not depend on separate thread-bearing flanges or bushings for structural strength and which is yet very strong and durable even when the particular sheet-metal from which the container is formed is relatively thin.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what is hereby claimed as new and desired to be secured by Letters Patent, is:

1. In a sheet metal container of the character described, a sheet metal panel having an opening therein bounded by an integral outwardly extending generally cylindrical annular flange, the longitudinal axis of said flange being generally perpendicular to the plane of said panel at the base of the flange, the wall of said flange being helically corrugated and having its inner surface adapted for direct screw-threaded engagement with the threaded outer surface of a closure plug, the outer end portion of said flange being turned downwardly into juxtaposition with the panel metal surrounding the basal portion of said flange, and a relatively thick annular flange-reinforcing band of a lower melting point metal, cast in situ, extending around solely the outer surface of said flange and reaching from the panel metal at the base of said flange to the juxtaposed downturned outer end portion of said flange, the metal of said cast band extending into and snugly filling the troughs of said helical corrugations in the flange wall, whereby said cast band is non-rotatable relative to said flange and snugly backs said flange in a zone generally coextensive with its zone of screw-threaded engagement with said closure plug thereby materially strengthening said flange around said zone, said cast band being generally confined to the immediate vicinity of the panel opening, but not extending thereto.

2. In a sheet metal container of the character described, a sheet metal panel having an opening therein bounded by an integral outwardly extending generally cylindrical annular flange, the longitudinal axis of said flange being generally perpendicular to the plane of said panel at the base of said flange, the inner surface of said annular flange being adapted for intimate direct engagement with the outer surface of a closure plug

5 securely anchorable therein, the outer end portion of said flange being turned downwardly into juxtaposition with the panel metal surrounding the basal portion of said flange, said latter panel metal bearing undulating corrugations extending in generally radial directions, and a relatively thick annular flange-reinforcing band, cast in situ, extending around solely the outer surface of said flange and reaching from the corrugated panel metal at the base of said flange to the juxtaposed downturned outer end portion of said flange, the metal of said cast band extending into and snugly filling the troughs of said corrugations, whereby said cast band is non-rotatable relative to said flange and snugly backs said flange in a zone generally coextensive with the zone of engagement between said flange and said closure plug thereby materially strengthening said flange around said zone, said cast band being generally confined to the immediate vicinity of the panel opening, but not extending thereto.

10 3. In a sheet metal container of the character described, a sheet metal panel having an opening therein bounded by an integral outwardly extending generally cylindrical annular flange, the outer end portion of said flange being turned downwardly to provide a generally flat annular surface, and an annular flange-reinforcing band, cast in situ of a lower melting point metal, encircling said flange, said cast band including a generally flat annular end surface co-planar with and in direct continuation of the aforesaid annular surface, said co-planar annular surfaces compositely providing a generally flat gasket seat adapted to receive a sealing gasket.

15 4. In a sheet metal container of the character described, a metal panel having an opening therein bounded by an outwardly extending generally cylindrical flange having its longitudinal axis generally perpendicular to the plane of the panel at the base of said flange, a cast reinforcing band, cast in situ of a lower melting point metal, encircling said flange and in continuous intimate contact therewith throughout their zone of overlap, said cast reinforcing band including a well-defined shoulder extending around the outer surface of said band over which the lower skirt portion of a sheet metal sealing cap may be crimped to anchor said cap to said cast band.

HOWARD W. DODSON.
